(57) **CLAIM**

I claim the ornamental design for a fan with pan-shaped base, as shown and described.

DESCRIPTION

FIG. 1 is a front perspective view of the fan with pan-shaped base in a first position;

FIG. 2 is a rear perspective view of the fan with pan-shaped base in a first position;

FIG. 3 is a front elevational view of the fan with pan-shaped base in a first position;

FIG. 4 is a rear elevational view of the fan with pan-shaped base in a first position;

FIG. 5 is a side elevational view of the fan with pan-shaped base in a first position;

FIG. 6 is a side elevational view of the opposed side of the fan with pan-shaped base in a first position;

FIG. 7 is a top plan view of the fan with pan-shaped base in a first position;

FIG. 8 is a bottom plan view of the fan with pan-shaped base in a first position;

FIG. 9 is a front perspective view of the fan with pan-shaped base in a second position;

FIG. 10 is a rear perspective view of the fan with pan-shaped base in a second position;

FIG. 11 is a top plan view of the fan with pan-shaped base in a second position;

FIG. 12 is a bottom plan view of the fan with pan-shaped base in a second position;

FIG. 13 is a side elevational view of the fan with pan-shaped base in a second position;

FIG. 14 is a side elevational view of the opposed side of the fan with pan-shaped base in a second position;

FIG. 15 is a front elevational view of the fan with pan-shaped base in a second position; and,

FIG. 16 is a rear elevational view of the fan with pan-shaped base in a second position.

In the drawings, the broken lines depict unclaimed environment.
